(57) **CLAIM**

The ornamental design for a capillary tag as shown and described.

DESCRIPTION

FIG. 1 is a perspective view of an aspect of the invention;
FIG. 2 is a front elevation view thereof;
FIG. 3 is a rear elevation view thereof;
FIG. 4 is a right side elevation view thereof;
FIG. 5 is a left side elevation view thereof;
FIG. 6 is a top plan view thereof;
FIG. 7 is a bottom plan view thereof;
FIG. 8 is a perspective view of another aspect of the invention;
FIG. 9 is a front elevation view thereof;
FIG. 10 is a rear elevation view thereof;
FIG. 11 is a top plan view thereof; and,
FIG. 12 is a bottom plan view thereof.

The broken lines shown are included for the purpose of illustrating portions of the capillary tag that form no part of the claim.

1 Claim, 9 Drawing Sheets
